UNITED STATES PATENT OFFICE.

EDMUND H. TURNER, OF FERGUS FALLS, MINNESOTA.

DEVICE FOR HITCHING HORSES.

SPECIFICATION forming part of Letters Patent No. 392,834, dated November 13, 1888.

Application filed July 10, 1888. Serial No. 279,521. (No model.)

To all whom it may concern:

Be it known that I, EDMUND H. TURNER, of Fergus Falls, in the county of Otter Tail and State of Minnesota, have invented a new 5 and Improved Device for Hitching Horses, of which the following is a full, clear, and exact description.

This invention relates to devices for hitching horses, and has for its object to provide a 10 horse-hitching device so constructed that it will be firmly and securely held in place.

The invention consists in a horse-hitching device constructed and arranged as hereinafter described and claimed.

15 Reference is to be had to the accompanying drawings, forming a part of this specification, in which similar figures of reference indicate corresponding parts in all the views.

Figure 1 is a plan view of the device secured 20 in position for use. Fig. 2 is a vertical section on the line *x* *x*, Fig. 1; and Figs. 3 and 4 are detail views thereof detached.

In the construction of this invention, which is especially adapted to be secured in a crack in 25 planking, such as a board fence or a board sidewalk, I employ a ring-plate, 1, to which a hitching strap may be secured, having a flange, 2, with teeth 3 and spurs 4, the ring-piece 1 being inclined to the flange 2. In securing the ring-piece 1 in position the flange 2 is inserted 30 between two planks, 5, 5, with the teeth 3 and spurs 4 pressing against the edges of the planks. The teeth 3 and spurs 4 are of sufficient relative length, as shown, to allow for 35 the angle at which flange 2 is located with reference to the edges of planks 5. With the ring-piece 1 is employed a fastening device consisting of a pair of spikes, 6, having a cross-piece, 7, connecting them together. One of 40 the spikes 6 extends through a slot, 8, in the ring-plate 1 on one side of the flange 2, and the other extends down on the opposite side

of flange 2. The spikes are driven in between the planks 5 in the crack in which is located flange 2 and wedge the flange 2 at its ends, so 45 that the teeth 3 and spurs 4 are forced into the edges of the planks 5, the slot 8 permitting the flange 2 to move slightly in a diagonal direction to the crack between the planks. The result of this construction and arrangement of 50 parts is that any strain or pull by a hitching-strap fastened to ring-piece 1 will cause the spikes 6, with their cross-piece, 7 to more firmly wedge and lock the ring-piece in position, its teeth 3 and spurs 4 being pressed into the 55 planks.

The parts are made of metal and of suitable size to avoid breaking.

Having thus described my invention, what I claim as new, and desire to secure by Letters 60 Patent, is—

1. A horse-hitching device consisting of a ring-piece having a slot and a toothed flange adapted to be secured between two planks or wooden supports, in combination with a fastening device consisting of a cross-piece with spikes, one of which passes through the slot in the ring-piece and the other bears against the outside of the toothed flange, substantially as described. 65

2. A horse-hitching device consisting of a ring-piece with a slot and toothed flange, in combination with a wedging-spike fastener, substantially as described. 70

3. A horse-hitching device consisting of a ring-piece, 1, having a flange, 2, with teeth 3 and spurs 4, and a slot, 8, in combination with a fastener consisting of spikes 6 and cross-piece 7, substantially as described. 75

EDMUND H. TURNER.
